(57) **CLAIM**

The ornamental design for a portable electric drill body, as shown and described.

DESCRIPTION

FIG. 1 is a front perspective view of a portable electric drill body showing our new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof; and,

FIG. 9 is a front perspective view of the portable electric drill body in accordance with our new design illustrating a state in which environmental structures (a battery and a side handle) are attached to the portable electric drill body.

The broken lines in the drawings illustrate the environmental structures or portions of the portable electric drill body which form no part of the claimed design.
